UNITED STATES PATENT OFFICE.

ROY A. WHITE, OF WALKER TOWNSHIP, KENT COUNTY, MICHIGAN, ASSIGNOR TO AMERICAN SEATING COMPANY, OF GRAND RAPIDS, MICHIGAN, A CORPORATION OF NEW JERSEY.

LINK HINGE.

Application filed February 25, 1928. Serial No. 256,829.

This invention relates to a link hinge and more particularly to a floating hinge for use in conjunction with seat supporting legs of folding or collapsible chairs.

5 The main objects of this invention are to provide an improved form of floating hinge; to provide a link hinge for use in conjunction with seat supporting legs of folding chairs; to provide a hinge for folding chair 10 legs having improved means for equalizing strains on each of the chair stretchers; to provide a link hinge for seat supporting members whereby squeaks and like noises are minimized; to provide a link hinge for 15 folding chair legs to minimize unequal wear on each of the chair stretchers; to provide a link hinge which permits a maximum of close folding of the chair legs; and, to provide an improved form of link hinge having 20 a limited universal joint movement between the seat supporting legs.

An illustrative embodiment of the invention is shown in the accompanying drawings, wherein:

25 Figure 1 is a perspective view of a plurality of folding chairs secured together in alignment;

Figure 2 is a fragmentary sectional view showing the manner of securing the folding 30 chair legs by means of the improved form of link hinge;

Figure 3 is a fragmentary end view of the front and rear folding chair legs secured together by the improved form of link hinge; 35 and

Figure 4 is a plan view of the improved form of link hinge per se.

Referring to the drawings, a plurality of front legs 1 of a plurality of folding chairs 40 are secured together in alignment by a pair of transversely disposed stretchers 2. The stretchers are spaced apart and may be secured to the legs 1 on opposite sides thereof in any convenient manner. A plurality of rear legs 3 extend between the spaced stretchers 2 and are similarly secured in alignment by a single transversely disposed stretcher 4.

The front and rear legs are secured to-

gether by a link hinge 5 whose opposite ends 50 are pivotally connected to each of said legs respectively as by screws to provide a floating hinge therebetween in order that the weight on the seats 6 will be equally sustained by each of the stretchers 2. One end 55 of the link hinge is provided with a concave-convex portion 7 whose convex portion bears against the surface of the long leg 1 at its pivotal connection with the rear leg 3 in order to provide for a limited universal 60 joint movement as well as a floating hinge between the respective pairs of front and rear legs.

The seats 6 are supported by the upper 65 ends of the legs 3 and are pivotally connected at their respective backs to the legs 1 which are considerably longer in order to provide supports for the chair backs 8.

Thus it will be seen that the improved 70 form of link hinge is particularly adapted for equalizing seat weight strains on each of the stretchers and it likewise provides for a limited universal joint movement between the seat supporting legs of folding chairs.

While but one specific embodiment of the 75 invention has been herein shown and described, it will be understood that numerous details thereof may be altered or omitted without departing from the spirit of the invention defined by the following claims.

I claim:

1. In a folding chair, a pair of front legs and a pair of rear legs, a pair of stretchers transversely and spacedly secured to one pair of said legs on opposite sides thereof and adjacent opposite sides of the other pair of legs, link hinges pivotally connecting the front and rear legs, the upper ends of the links being secured to the said front legs, 85 and the lower ends of the links being secured to the rear legs below the points of intersection of the front and rear legs whereby the said legs are supported by the stretchers and accommodate themselves to uneven supporting surfaces.

2. In a folding chair, a pair of legs, a pair of stretchers transversely and spacedly

secured to one of said legs and adjacent opposite sides of the other leg, and a link hinge whose opposite ends are each pivotally secured to each of said legs, one end of said link having a concave portion contacting one of said legs to provide a limited universal joint movement between said legs for

equalizing the bearing portions of the legs intermediate the stretchers when said legs are resting upon uneven surfaces.

10

In testimony whereof I have hereunto set my hand at Grand Rapids, Michigan, this 22nd day of February, 1928.

ROY A. WHITE.
